UNITED STATES PATENT OFFICE.

ALOYS WIRSCHING, OF BROOKLYN, NEW YORK.

DEVICE FOR ATTACHING INDEX-FINGERS TO ARBORS.

No. 892,021.

Specification of Letters Patent.

Patented June 30, 1908.

Application filed March 11, 1908. Serial No. 420,370.

To all whom it may concern:

Be it known that I, ALOYS WIRSCHING, a citizen of the United States, residing at Brooklyn, in the county of Kings and State 5 of New York, have invented a certain new and useful Improvement in Devices for Attaching Index-Fingers to Arbors, of which the following is a specification.

The invention relates to the attachment of 10 index fingers to arbors and consists in the device hereinafter set forth, whereby said attachment may be effected without the use of pins, screws, or any parts additional to the arbor and index finger to be connected.

The invention is applicable to all apparatus wherein moving index fingers are employed, such as clocks, and especially the minute hands thereof, gages, registers, and 20 measuring instruments of all kinds.

In the accompanying drawings—Figure 1 shows part of a dial, the index fingers thereon and supporting arbor. Fig. 2 is an end view of the arbor. Fig. 3 is an enlarged 25 side elevation of the arbor with the index finger in place thereon. Fig. 4 is a section on the line $x x$ of Fig. 3.

Similar letters of reference indicate like parts.

The arbor A which may be vibrated or 30 rotated in any suitable way has, near its end, a shoulder B. The end portion C of said arbor beyond said shoulder is polygonal and preferably rectangular, in cross section, 35 as shown. Adjacent to the shoulder said portion C is of contracted cross-sectional area and may be provided with a peripheral groove D. It is also bifurcated, the bifurcations being separated by a wedge shaped 40 recess E, preferably symmetrically placed and terminating in a transverse hole F. A portion of the metal of the arbor, on each side and opposite the hole F may be cut away as shown at G.

H is an index finger formed in the usual 45 way of thin metal and having at one end an enlarged portion I, in which is a polygonal opening corresponding in shape to the cross section of the polygonal portion C of arbor

A, but about equal in area to a cross section 50 taken through the groove D on the line $x x$ Fig. 3, and hence somewhat less in area than a cross section of the portion C beyond said groove.

In order to attach the index finger to the 55 arbor, the bifurcations of the arbor are pinched together by the hand of the operator, so that the portion C can be inserted in the opening in the finger as shown in Fig. 3. The finger plate I is then received in the 60 groove D, and rests on shoulder B. The bifurcations being released spring back to normal position and the finger is thus firmly retained in place in the groove D. The finger is thus prevented from coming off the arbor, 65 unless the parts of said arbor are brought together by the hand of an operator, as before.

The object of the hole F and the cut away portions G is to make the bifurcations of the 70 arbor more elastic and yielding.

I claim:

1. In combination with an index finger having a polygonal opening, an arbor having a bifurcated end of corresponding cross 75 section to said opening: the said bifurcated portion having a peripheral groove and constructed to enter said finger opening when said bifurcations are approximated: and the said finger being thereafter retained in said groove solely by the resilient return of said bifurcations to normal position.

2. In combination with an index finger having a polygonal opening, an arbor having an integrally formed shoulder and a bifurcated portion beyond said shoulder of corresponding cross section to said opening: the said end portion being of contracted cross sectional area immediately adjacent to said shoulder and being constructed to enter 90 said finger opening when the bifurcations are approximated: and the said finger being thereafter retained on said shoulder solely by the resilient return of said bifurcations to normal position.

3. In combination with an index finger having a polygonal opening, an arbor having an integrally formed shoulder and a bifur-

cated end portion beyond said shoulder of corresponding cross section to said opening: the said end portion having a peripheral groove adjacent to said shoulder and being constructed to enter said finger opening, when the bifurcations are approximated: and the said finger being thereafter retained in said groove and on said shoulder solely by the

resilient return of said bifurcations to normal position.

In testimony whereof I have affixed my signature in presence of two witnesses.

ALOYS WIRSCHING.
